Inventor:

Nathaniel Russell

Dec. 1132

Nathaniel E. Russell, of New York, N. Y.
Letters Patent No. 1132, dated Aug. 9, 1859.

The schedule referred to in these Letters Patent and making part of the same.

To all whom it may concern:

Be it known that I, Nathaniel E. Russell, of the City of

County and State of New York, have invented or produced a new and original Design for a Table Fork, and I do hereby declare that the following is a full, clear and exact description of the same, reference being had to the annexed drawings making a part of this Specification, in which -

Figure 1, is a view of the inner or concave side of a table fork constructed according to my design.

Figure 2, is an end view of ditto.

Figure 3, is a view of the back or concave side of ditto.

Similar letters of reference indicate corresponding parts in the several figures.

This design pertains to that portion of a table fork which is technically termed the neck and stem which parts are included between the bolster that abuts against the handle and the bosom at the inner ends of the tines.

The neck designated by a, is a recess or groove which transversely is of semi-circular form. This recess or groove extends entirely around the fork immediately adjoining the bolster b, which abuts against the end of the handle c. The recess or groove is of octagonal form, as shown clearly in all the figures.

The stem d, is also of octagonal form corresponding with the recess or groove a. The stem longitudinally is of concave form on each face or side, gradually decreasing in diameter from the recess or groove a, to its central portion and then gradually increasing in diameter to the bosom e, which is the usual form, the bosom, tines, bolster and handle forming no part of the design.

Having thus described my invention what I claim as new and desire to secure by Letters Patent, is

The configuration of the neck and stem as shown and described to form a new and original design for a table fork.

End Witnesses.

S. M. B. W. M. Livingston,
Mich Hughes.

Nathaniel E. Russell.
